METHOD AND APPARATUS FOR HEATING ROLLS

Filed March 3, 1924

2 Sheets-Sheet 1

Fig. 1.

rolled. Expressed in other language, during the preliminary heating the heat is of low intensity whereby to permit the relatively uniform distribution thereof throughout the rolls to prevent damage due to strains produced by too rapid local expansion. After the preliminary heating a heat at a higher intensity is applied to bring the rolls to the proper temperature and to the proper conformation at the same time.

It is an object of the present invention to provide a new and improved method and apparatus for heating rolls.

It is a further object to provide apparatus of this character which is relatively light and which may be moved about and applied to the rolls without moving them from the roll stands.

It is an additional object to provide a heater in which the degree of heat may be controlled and in which distribution of the heat to the various portions of the roll may be properly taken care of.

It is also an object of the present invention to provide heating means in which the heat may be transmitted to the rolls by direct metallic contact.

Other and further objects of the invention will appear as the description proceeds.

Efforts have heretofore been made to heat rolls by the application of steam jackets or by blowing heated air or gases upon the rolls. These methods do not allow for an adequate temperature range or control of the temperature, or of application of differing amounts of heat to the various portions of the roll. Moreover, they do not allow for the application of heat by the most economical method of direct metallic contact. Since the rolls vary in diameter and contour due to variation in heat, it is essential that the heating means be flexible if it is to maintain contact with the rolls throughout the heating operation.

We have illustrated in the accompanying drawings, a preferred embodiment of our invention.

In these drawings—

Figure 1 is an elevation with the heating means applied to the rolls in the stand, the rolls being shown in section;

Figure 2 is a view on an enlarged scale, of a portion of Figure 1, showing in detail the connection of the heating elements;

Figure 3 is a fragmentary view showing the heater applied to the rolls as seen from the right of Figure 1;

Figure 4 is a detail view, partly broken away showing one of the heating elements;

Figure 5 is a fragmentary view illustrating the contact of the heating element with the roll; and

Figures 6, 7 and 8 are somewhat diagrammatic views illustrating circuits suitable for our heating means.

Referring particularly to Figure 1, the upper roll 11 and lower roll 12 are shown supported in a usual type of roll stand 13. This roll stand which is of usual construction, forms no part of our present invention and will not be described in detail. The roll heater comprises two separate elements A and B, one of which is applied to each side of the pair of rolls. These elements are exactly similar and the description of one applies to the other. The elements comprise a frame 14 of angle bars from which the handles 15 extend at the upper end and the rollers 16 extend at the lower end. The two elements A and B are clamped together by means of the bolts 17 and 18 at their upper and lower ends. The flexible jacket members 19 are secured to the upper portion of the frame and the similar jacket members 20 are secured to the lower portion of the frame. It will be noted that the jackets 19 and 20 are secured to the frames only through a small portion of their periphery, the remainder of which remains flexible and free to be drawn in contact with the rolls. The adjusting bolts 21 are threaded through the transverse frame members 22 and are provided with the enlarged ends 23 engaging the upturned edges 24 and 25 of the jackets 19 and 20.

As shown in detail in Figure 2 the jacket 19 is provided with a lining 26 of asbestos or similar heat insulating material. The plurality of heating elements 27 are secured upon the inner face of the insulating material and are provided with the connector lugs 28. The several heating elements are connected in parallel by the connectors 29. It will be noted that the heating elements 27 are more closely spaced at the upper and lower portions of the jacket than at the intermediate portion thereof. This for the purpose of uniformly distributing the heat throughout the periphery of the roll. These more closely spaced units are located nearer the gaps at the top and bottom of the roll where no units are in contact with the rolls. Due to the actual contact of the heat elements with the roll the heat is quickly transmitted through the metal of the roll to these portions not in direct contact with heating elements. It is to be understood, however, that although the greatest efficiency is accomplished by maintaining the heating elements in contact with the roll, it is possible to heat the roll without direct metallic contact.

Referring now to Figure 5, the heat element 27 is shown in full lines in its normal or cooled state. In dotted lines is indicated how the element will be bowed outwardly when it expands upon being heated. This outward bowing of the element will force it into intimate contact with the roll 11.

One form of heating element is shown in

from such elements to the rolls during an initial heating period at a relatively low rate, whereby the heat is distributed through the roll in a manner to minimize internal stresses, and subsequently connecting such heating sections in series parallel whereby the rate of heat supply is increased.

10. In combination, a roll, a pair of electrical heating elements extending longitudinally of said roll, each of said heating elements comprising a resistor arranged to have a varying heating effect longitudinally of the corresponding element.

Signed at Chicago, Illinois, this 26th day of Feb., 1924.
